(57) **CLAIM**

The ornamental design for an edible beverage umbrella as shown and described.

DESCRIPTION

FIG. 1 is a top view of an edible beverage umbrella showing our new design;

FIG. 2 is a side view of the edible beverage umbrella shown in FIG. 1; and,

FIG. 3 is a bottom view of the edible beverage umbrella shown in FIG. 1.

The broken lines shown in the figures form no part of the claimed design.

The stippled shading and line shading shown in FIGS. 1-3 represent a contrasting appearance.
